UNITED STATES PATENT OFFICE.

EDWARD GRAND, JR., OF OTTAWA, ONTARIO, CANADA.

FLEXIBLE COVER FOR DRAFTING-TABLES, DESKS, AND THE LIKE.

1,143,901.

Specification of Letters Patent. Patented June 22, 1915.

Application filed May 7, 1914. Serial No. 837,098.

To all whom it may concern:

Be it known that I, EDWARD GRAND, Jr., a subject of the King of Great Britain, and a resident of the city of Ottawa, in the county of Carleton, Province of Ontario, Canada, have invented certain new and useful Improvements in Flexible Covers for Drafting - Tables, Desks, and the like, of which the following is a specification.

- 10 My invention relates to improvements in flexible covers for drafting tables, desks and the like as described in the present specification and illustrated by the accompanying drawings forming part of the same.
- 15 The invention consists essentially in the combination with a tubular casing formed with a longitudinally extending aperture, and provided with securing brackets, of a spring actuated roller carrying a flexible 20 cover adapted to fit therein.

The objects of my invention are to provide a new, simple and inexpensive device of this class particularly adapted for covering, to any required extent, drawing tables, 25 desks and the like thus preserving the objects thereon from dust, and, as the flexible material may be waterproof, from damp.

A further object is to provide a cover of this class that will be absolutely flexible and 30 so arranged as to cover objects on the whole table or desk or on a portion thereof.

With these and other objects in view reference is now had to the accompanying drawings in which like letters of reference 35 indicate corresponding parts in each figure, and in which—

Figure 1 is an isometrical view showing my device attached to a table. Fig. 2 is an enlarged section on line X—X of Fig. 1 40 looking in the direction of the arrow. Fig. 3 is a view showing the longitudinally apertured tube or casing with a spring operated roller in dotted lines therein. Fig. 4 is an enlarged plan view showing part of casing. 45 Fig. 5 is a view of the movable end closing lock for tube. Fig. 6 is an isometrical view of the closing end lock.

Referring to the drawings. A is the table having fixedly secured thereto my improved 50 device B, consisting of the tubular portion or casing E formed with a longitudinally extending aperture or slot. One of the sides of said slot or aperture being folded over to form the longitudinally extending tubular bead e, and the other side of said slot being

bent to first form the lip or runner e'', and the corresponding longitudinally extending pipe like bead e'. Said beads e and e' being adapted to receive the locking means of the movable end of the casing E, hereinafter 60 more fully referred to.

F are a plurality of brackets for securing the tube to the table or desk as shown in Figs. 1 and 2. While one end of the tube or casing is formed integral therewith, the 65 other end is provided with a movable locking end K folded at m to form a hinge or securing means for a staple formed with the prongs l and l', adapted to fit into the tubular beads e and e'. 70

N is the tubular portion or collar of the locking end k. Within the tubular casing is a spring actuated roller d having folded thereon the flexible cover or cloth C', and provided with a square end g, and end g² 75 adapted to fit respectively into the sockets g' and g³, in the ends of the tube e.

H is a reinforcing wire used in folding the sides of the slot, and I is a loop formed at one end of the casing E to correspond 80 with the loop formed at the other end by the locking end on k.

From the foregoing the operation of my device will be apparent. The rolled flexible sheet having been placed in the tube and 85 securely locked therein by the insertion of the prongs l and l' in the beads e and e' is ready to be drawn out by means of the ring thereon p, as shown in Fig. 2. The roller for said sheet being spring operated, said sheet can be extended to cover the whole of the table A or only a portion thereof and retained in these positions. 90

By the above-mentioned construction it will be noticed that the flexible sheet is always in position for use, and is adapted to run only in the way required, and can be readily retracted and cased when not in use. 95

What I claim for my invention is: 100

A device of this class described consisting of a tube or casing of suitable material formed with a longitudinally extending slot or aperture therein, one of the edges of said slot being folded to form a longitudinally 105 extending pipe like bead, and the other of said edges being folded to form a runner or lip, and underneath a corresponding extended pipe-shaped bead, movable locking means for one end of said casing comprising a 110

hinged portion, a pronged staple therein adapted to fit into said pipe-shaped beads, whereby the sides of the casing aperture are held together; a spring actuated roller 5 adapted to fit into and operate in said casing, a flexible waterproof cover wound on said roller, means in the ends of said casing adapted to hold said roller, reinforcing means for said folded sides of the casing-
10 aperture, said casing provided with a plu-

rality of brackets for fixedly securing it in position.

In testimony whereof I have hereunto signed my name in the presence of the undersigned witness at the city of Ottawa, 15 this 29th day of April, 1914.

EDWARD GRAND, JR.

Witness:

W. T. CUFFE-QUIN.
